CLAIM

The ornamental design for a combined limit band and tether for an exercise and fitness device, as shown and described.

DESCRIPTION

FIG. 1 is a front perspective view of a combined limit band and tether for an exercise and fitness device of the present invention showing our new design;

FIG. 2 is a front elevational view thereof;

FIG. 3 is a back elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines illustrate portions of the combined limit band and tether for an exercise and fitness device which form no part of the claimed design.
